UNITED STATES PATENT OFFICE.

STEPHEN C. PRICE, OF LOUISIANA, MISSOURI, ASSIGNOR TO FRANK W. BUFFUM, OF LOUISIANA, MISSOURI.

POURING DEVICE FOR BOTTLES AND THE LIKE.

Application filed October 17, 1921. Serial No. 508,213.

To all whom it may concern:

Be it known that I, STEPHEN C. PRICE, a citizen of the United States, and resident of the city of Louisiana, county of Pike, and 5 State of Missouri, have invented certain new and useful Improvements in Pouring Devices for Bottles and the like, of which the following is a specification containing a full, clear, and exact description, reference being 10 had to the accompanying drawings, forming a part hereof.

My invention relates to improvements in pouring devices for bottles and the like and has for its primary object the construction 15 of a device which may be readily applied to and removed from a bottle neck and facilitates the discharge of the contents from the bottle.

In the drawings—

20 Fig. 1 is a side elevation of a bottle showing my improvement applied thereto; and

Fig. 2 is a longitudinal section of the bottle and a fragmental section of my device.

25 Referring to the drawings, 3 indicates a bottle of any desired construction and 4 the bottle neck.

My device consists essentially of a discharge spout 5, which may be constructed 30 of any material and made either rigid or flexible, as desired. Secured to the dis-

charge spout 5 is a housing 6 which is adapted to be inserted over the top of the bottle neck as illustrated in Figs. 1 and 2. The housing 6 is provided with an in- 35 tegral shoulder 7, which is adapted to rest or be seated on the top edge of the bottle neck, as illustrated in Fig. 2. Secured to the housing 6 is a series of spring clamps 8, each of which is provided with an internal

40 groove 9 in which the rib 10 is seated when the device has been applied to the bottle neck. Mounted in the housing 6 is a vent pipe or tube 11, the upper end 12 of which projects beyond the housing. The purpose of this 45 vent pipe is to admit air into the bottles or container to facilitate the discharge of its contents.

Telescopically mounted on the vent pipe

12 is a pipe 13, the lower end of which is slotted as at 14. By means of the pipe 13 50 the vent pipe may be adjusted for different depths or sizes of bottles.

My device may be applied to various sizes of bottles and may be arranged to be applied in the bottle neck in place of over it, as 55 illustrated. It is highly useful for the discharge of lubricants and other heavy oils or liquids, and of course may be used to discharge any liquid from the vessel.

Having fully described my invention, 60 what I claim is:

1. A pouring device for bottles and the like comprising a discharge spout, a housing secured to one end thereof and adapted to be seated over the discharge end of a container, 65 a vent pipe carried by the housing and having one end extending beyond the exterior surface thereof, and its other end adapted to be placed within the container.

2. A pouring device for bottles and the like, comprising a flexible discharge spout a housing secure to one end thereof and adapted to be seated over the discharge end of a container, a vent pipe carried by the housing and having one end extending beyond the exterior surface thereof, and its other end adapted to be placed within the container. 75

3. A pouring device for bottles and the like, comprising a flexible discharge spout, 80 a housing secured to one end thereof and adapted to be seated over the discharge end of a container, an adjustable vent pipe carried by the housing and having one end extending beyond the exterior surface thereof, 85 and its other end adapted to be placed within the container.

4. A pouring device for bottles and the like, comprising a discharge spout, a housing secured thereto, spring arms secured to 90 the housing, said housing and arms adapted to embrace a bottle neck, and a vent pipe carried by said housing.

In testimony whereof, I have signed my name to this specification.

STEPHEN C. PRICE.
